UNITED STATES PATENT OFFICE.

FRANKLIN S. UPHAM, OF DES MOINES, IOWA.

TOY TRAIN COUPLING.

Application filed April 16, 1927. Serial No. 184,356.

The object of my invention is to provide a toy train coupling device of simple, durable and comparatively inexpensive construction.

More particularly it is my object to provide a coupling device primarily adapted for use in connecting and coupling together a number of toy trains or the like wherein the cars when coupled together will be held in connected relationship and where the coupling can be easily and quickly detached.

Still a further object is to provide an opening in one end of the car for receiving one part of a coupling device and to provide a control pin for coacting with the first part of the coupling device wherein the cars will be coupled together.

Still another object is to provide a control pin that is frictionally held in the toy car itself and remains in the position to which it is moved.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side view of a toy train having my coupling device shown thereon.

Figure 2 is a sectional view taken through the ends of adjacent cars illustrating the coupling device.

Figure 3 is a sectional view taken on the line 3—3 of Figure 2 and

Figure 4 is a side view of the control pin forming a part of the coupling device.

In the accompanying drawings I have used the reference numeral 10 to indicate an ordinary body of a toy car which is mounted upon wheels or the like 12. Each car 10 of the train may be formed of different shapes so that there will be an engine, a tender, a tank car, a box car and a caboose.

In one end of one of the cars 10 is mounted a hook element 14 arranged with an eye 16. The hook element 14 forms one part of the coupling device and is extended into the car 10. The cars 10 are preferably made of wood and the hook 14 is simply pushed into position.

The eye 16 of the hook 14 is arranged to lie in a substantially horizontal plane. It will be noted that in one end of each of the

cars 10 is mounted a hook 14 having the eye 16 forming a part thereof. In the other end of each of the cars 10 is arranged a horizontal bore or notch 18 in communication with a vertical bore or opening 20.

The bore 18 is considerably larger than the opening 20. The eye 16 of the hook 14 is arranged to register with the opening 18 and to be received therein as clearly illustrated in Figures 2 and 3 of the drawings.

The opening 20 which is vertically arranged is in register with the eye 16 of the hook 14. A control or locking pin 22 is used for connecting or coupling together one car with the other. The control pin 22 is arranged with a vertical shank having a hook or loop 24 at its upper end. The control pin 22 is bent at its lower end as at 26 and continues with a side arm 28.

The entire control pin 22 is formed of 75 spring wire and the normal tendency of the control pin is to remain in the position as illustrated in Figure 4 of the drawings. At the lower end of the control pin 22 adjacent the bend 26 I form indents which are arranged to coact with the hook 14 within the eye 16.

The control pin 22 is inserted in the vertical opening 20 and when this is done the control pin 22 is compressed and placed under a tension which causes the control pin 22 to frictionally engage the sides of the opening 20.

The cars 10 are preferably made of wood so that a very good frictional engagement 90 is had between the control pin 22 and the sides of the opening 20. The pin 22 is designed to project into the opening 18 and through the eye 16, thus serving as a coupling means for connecting one car 10 with 95 the next adjacent car 10.

The cars may be disconnected by simply pulling the control pin 20 upwardly a slight distance or until its lower end clears the hook 14 at which time the cars may be disconnected.

It will be seen that in a toy train it is quite desirable to arrange a coupling device that is simple and one that permits the child to have something to manipulate 105 and operate. The cars may be uncoupled and rearranged and coupled up easily.

The opening 18 is of sufficient size so that when the hook 14 is placed therein and the pin 22 moved downwardly, the coupling is 110

insured. The frictional engagement retains the pin 22 in position where it serves to connect together the two adjacent cars.

The pin 22 when raised or disconnected from the hook 14 remains in its disconnected position due to the frictional engagement of the pin 22 with the sides of the opening. The upper end or loop 24 of the pin 22 projects above the car and serves as a handle 10 wherein the control pin 22 may be engaged for moving the pin 22 as desired.

Some changes may be made in the construction and arrangement of the parts of my device without departing from the real 15 spirit and purpose of my invention, and it is my intention to cover by my claims, any modified forms of structure or use of mechanical equivalents which may be reasonably included within their scope.

20 I claim as my invention:

1. A toy train coupling comprising a plurality of cars, a hook member connected to one end of each of said cars, each hook member having an eye therein arranged substantially horizontal, the other end of each of said cars having a vertical bore and a horizontal bore therein communicating with each other, said hook member having the eye portion thereof arranged to be received in said horizontal bore and means frictionally mounted in said vertical bore adapted to project through the eye of said hook member, said means having an enlarged portion adapted to project below the eye of the hook member.

2. A toy train coupling comprising a plurality of cars, a hook member connected to the end of one of said cars, said hook members having an eye therein arranged substantially horizontal, one of said cars having a vertical bore and a horizontal communicating bore therein, said hook member having the eye portion thereof arranged to be received in said horizontal bore and means frictionally mounted in said vertical bore adapted to project through the eye of said hook member, said last means frictionally engaging the walls of said vertical

bore for causing the said means to remain in any of its various positions when manually moved.

3. A car coupling for toy trains comprising a car having an eye member carried thereby, a second car having a vertical and a horizontal bore therein communicating with each other, said eye member being arranged to fit into said horizontal bore and in register with said vertical bore and a coupling pin comprising a spring wire substantially V-shaped and having an enlarged loop 55 at the junction point of the sides of the wire whereby said sides must be sprung toward each other when the coupling pin is inserted in the vertical bore and they will thereby frictionally engage the wall of said bore. 60

4. A car coupling for toy trains comprising a car having an eye member carried thereby, a second car having a vertical and a horizontal bore therein and in communication with each other, said eye member being arranged to fit into said horizontal bore and in register with said vertical bore, a control pin having two side parts connected together at their lower ends, said side parts frictionally engaging the walls of said vertical bore, said side parts at their connected ends being arranged to project through said eye member as and for the purposes stated. 75

5. A car coupling for toy trains comprising a car having an eye member carried thereby, a second car having a vertical and a horizontal bore therein and in communication with each other, said eye member being arranged to fit into said horizontal bore and in register with said vertical bore, a control pin having two side parts connected together at their lower ends, said side parts frictionally engaging the walls of said vertical bore, said side parts at their connected ends being arranged to project through said eye member and provided with an indent 80 for forming an enlarged head at their connected ends. 85

Des Moines, Iowa, March 8, 1927.

FRANKLIN S. UPHAM.
